UNITED STATES PATENT OFFICE.

LOUIS ESCUTCHEN, OF PHILADELPHIA, PENNSYLVANIA.

SCRAPING AND CLEANING DEVICE.

1,243,825.

Specification of Letters Patent. Patented Oct. 23, 1917.

Application filed January 13, 1917. Serial No. 142,194.

To all whom it may concern:

Be it known that I, LOUIS ESCUTCHEN, a citizen of the United States, residing at Philadelphia, in the county of Philadelphia and State of Pennsylvania, have invented certain new and useful Improvements in Scraping and Cleaning Devices, of which the following is a specification.

My invention consists of an improved 10 scraping and cleaning device, and is particularly adapted for use in scraping and cleaning the tops of butcher's and leather worker's chopping and cutting blocks.

One object of my invention is to provide 15 a device of the above described type which will include a power driven brush, and to inclose the brush within a hood or casing.

Another object is to so construct my invention that it can be firmly held in contact 20 with the article being cleaned.

A still further object is to make my invention of simple construction, and so that it can be easily manipulated.

These objects, and other advantageous 25 ends which will be described hereinafter, I attain in the following manner, reference being had to the accompanying drawings in which—

Figure 1 is a plan view of my invention.

Fig. 2 is an elevation of Fig. 1 showing certain of the parts in section.

Fig. 3 is a plan view of a brush which I employ, with its cover plate removed.

Fig. 4 is a fragmentary perspective view 35 showing how the adjustable portions of my improved casing are formed.

Fig. 5 is an enlarged fragmentary section taken on the line 5—5 of Fig. 3.

Referring to the drawings, 1 represents 40 an electric motor including a rotatable shaft 2 which is screw-threaded at its outer end 3 for engagement with a tapped hole 4 in the brush supporting plate 5. The plate 5 has a plurality of holes 6 extending there-through, and through these holes extend metallic bristles 7 (see Figs. 3 and 5).

These bristles are U-shape and the folded upper ends 8 of said bristles project beyond the upper face 9 of the plate 5. Wires 10 55 extend across the surface 9 of the plate 5 and under the ends 8 of the bristles 7, and thereby form a lock to prevent the downward movement of the bristles.

A cover plate 11 is secured to the plate 5 by means of screws 12, and this cover plate has a recess 13 which provides flanges 14 for

engagement with the upper surface 9 of the plate 5 and also provides room for inclosing the wires 10 and the upper ends of the bristles 7. By this construction the cover 60 plate 11 protects the upper ends of the bristles and also prevents upward movement thereof.

The bristles 7 are preferably made of flat 65 spring steel wire so that their lower ends form a plurality of cutting edges or knives and are of sufficient strength to cut or pare a wooden block or other similar article when the brush is rotated.

The upper surface of the cover plate 11 is 70 spaced from the motor 1 by means of a sleeve 15 which is attached to the motor and forms an abutment for said upper surface of the cover plate 11. This same spacing 75 also provides room for a head plate 16 which forms a part of a hood or casing 17 for the brush. The casing 17 has a skirt 18 which is made in two circumferentially extending sections 19 and 20. The section 19 is secured to the head plate 16 as shown at 21 80 by a lapped or interlocking joint. The section 20 slides or telescopes within the section 19 and is provided with slots 22 (see Fig. 2).

Bolts 23 extend through the slots 22 and 85 through holes 24, and at their outer ends are provided with butterfly nuts 25 whereby the section 20 may be clamped to the section 19. Also, by this construction, as the bristles 7 wear down and become shorter, the 90 section 20 may be slid within the section 19 from time to time and in proportion to the wear of the bristles 7. I thus provide an adjustable hood or casing which surrounds 95 the brush and in action this casing prevents the particles as they are cut from flying uncontrolled over the surface of the article being cleaned or re-surfaced.

In other words, the casing 17 acts to confine the particles as they are cut or removed 100 by the brush.

The motor 1 has laterally extending ears 105 26 which are diametrically opposite each other with respect to the axis of the shaft 2, and these ears form supports for two handles 27 and 28. Bolts 29 extend through the ears 26, handles 27 and 28, and the head plate 16 of the casing 17, so that the handles and casing 17 are securely held to the motor.

The motor may be rotated by current supplied through the medium of the wires 110 30

and plug 31, said wires being preferably in the form of a flexible cable so that the device may be freely moved without interference.

The handles 27 and 28 have ends 27^a and 28^a which extend inwardly beyond the bolts 29 and closely hug the motor (see Fig. 1). By this construction it is impossible for the handles 27 and 28 to swivel or turn on the bolts 29, and I thus provide a firm handhold 10 and prevent the handles from becoming loose.

It is well known that butcher's and leather worker's blocks often require cleaning or what is known as re-surfacing on account 15 of the many cuts and nicks which are formed by the cutting tools in the top of the blocks. With the use of my invention, these blocks may be cleaned and re-surfaced merely by starting the motor 1 to rotate 20 the brush and by holding the device by the aid of the handles sufficient pressure may be attained between the cutting or cleaning ends of the bristles 7 and the block which is being cleaned.

25 While I have described my invention as taking a particular form, it will be under-

stood that the various parts of my invention may be changed without departing from the spirit thereof, and hence I do not limit myself to the precise construction set forth, 30 but consider that I am at liberty to make such changes and alterations as fairly come within the scope of the appended claim.

Having thus described my invention, what I claim as new and desire to secure by Letters Patent is:

The combination of a rotatable brush, a motor for rotating the brush, handles, bolts connecting the handles and the motor together, said handles having portions extending inwardly from said bolts and operative to abut the motor and thereby prevent pivotal movement of the handles with respect to the bolts, substantially as described.

In testimony whereof I have signed my name to this specification in the presence of two subscribing witnesses.

LOUIS ESCUTCHEN.
